US00D833857S

(12) **United States Design Patent** (10) **Patent No.:** **US D833,857 S**
(45) **Date of Patent:** **** Nov. 20, 2018**

(54) **FASTENER**

(71) Applicant: **GRIPPLE LIMITED**, Sheffield (GB)

(72) Inventors: **Lee Giemza**, Wakefield (GB); **Robert Hepworth**, Sheffield (GB)

(73) Assignee: **GRIPPLE LIMITED**, Sheffield (GB)

(**) Term: **15 Years**

(21) Appl. No.: **29/595,812**

(22) Filed: **Mar. 2, 2017**

(30) **Foreign Application Priority Data**

Sep. 7, 2016 (EM) 003368711-0005

(51) **LOC (11) Cl.** **08-08**

(52) **U.S. Cl.** ..... **USPC** **D8/382**

(58) **Field of Classification Search**

USPC D8/60, 61, 77, 82, 342, 349, 354, 355, D8/356, 367, 382, 396, 499; D23/213, D23/219, 223-227

CPC B25B 1/205; B25B 1/103; F16G 11/04; F16B 13/08
